Attorney

UNITED STATES PATENT OFFICE.

EDLA M. GOURLEY, OF ASHTON, NEBRASKA.

TATTING-THIMBLE.

1,260,187.

Specification of Letters Patent. Patented Mar. 19, 1918.

Application filed January 15, 1917. Serial No. 142,493.

To all whom it may concern:

Be it known that I, EDLA M. GOURLEY, a citizen of the United States, and resident of Ashton, in the county of Sherman and State of Nebraska, have invented certain new and useful Improvements in Tatting-Thimbles, of which the following is a specification.

The present invention relates to improvements in thimbles and has particular reference to a novel and improved type of tatting thimble having means associated therewith to facilitate weaving of the thread or strand of cotton employed for this purpose.

An object of my invention is to provide a thimble of the class referred to adapted to be received upon one of the fingers of the user's hand, said thimble having a notched hook member on the closed end thereof for engagement with the thread being woven.

My invention contemplates the provision of a hook on a thimble whereby to obviate the necessity of using a crochet hook, it being necessary to pick up the hook for use every few movements of the thread, this being the cause of considerable loss of time when using a separate crochet hook.

Another object of my invention is to provide a tatting thimble of the class described having a hook associated therewith which enhances the efficiency of such thimbles, is simple in construction, and occupies a minimum amount of space and does not interfere in any manner with the usual use of the shuttle.

Other objects and advantages to be derived from the use of my improved tatting thimble will appear from the following detailed description and the claims, taken with an inspection of the accompanying drawing, in which:

Figure 1 is a perspective view of a tatting thimble embodying the improvements of my invention, the same being shown in position for use on a hand; and

Fig. 2 is a fragmental elevational view of the same.

Referring more particularly to the drawing, wherein similar characters of reference designate like and corresponding parts

throughout the various views, 10 designates in its entirety a thimble having the usual construction, the outer surface thereof being roughened as at 11 in the usual manner. 55

My invention includes a hook member formed of a wire strand or the like 12 extending from the end wall 13 of the thimble at the center point thereof. The strand 12 is bent intermediate its ends laterally to 60 form a hook 14, said hook having a recess 15 therein on the inner side thereof.

In use the thimble is placed upon one of the fingers of the user's hand, the middle or usual thimble receiving finger 16 being 65 shown as receiving the thimble in Fig. 1. In lieu of the usual crochet hook the hook 14 of my invention is used, the same being inserted through the interstices of a garment woven by the tatting process in order to 70 reach strands of cotton, silk or the like to draw the same through the said interstices. In the manner of performing this process at the present time the user finds it necessary to pick up a crochet hook and use it for 75 this purpose. Thus it will be seen that my invention entirely obviates the necessity of a separate implement such as a crochet hook, the hook being carried by the thimble.

From the above description taken in connection with the accompanying drawing, it is thought that a clear and comprehensive understanding of the construction, operation and advantages of my invention may be had, and while I have shown and described the 85 device as embodying a specific structure, I desire that it be understood that such changes may be made in said structure as do not depart from the spirit and scope of the invention as claimed. 90

Having thus fully described my invention, what I claim as new and desire to secure by Letters Patent, is:—

1. The combination with a thimble having the usual closed end, of a tatting hook carried thereby, said tatting hook extending from said closed end and being bent laterally from the thimble. 95

2. The combination with a thimble having the usual closed end, of a tatting hook 100 formed of a strand of wire connected to the central portion of said closed end and ex-

tending longitudinally therefrom, the free end of said strand being bent laterally to form a hook and provided with a recess.

3. The combination with a thimble having 5 the usual closed end, of a hook, said hook being formed with a strand of wire connected at one of its ends to the central portion of the end wall of said thimble, the free

end of said strand being bent laterally to form a hook, said laterally bent portion being provided with a recess on the inner side thereof for the purpose specified. 10

In testimony whereof, I affix my signature hereto.

MRS. EDLA M. GOURLEY.
